UNITED STATES PATENT OFFICE

2,463,867

DAMPING UNIT FOR WATT-HOUR METERS

Stanley S. Green, La Fayette, Ind., assignor to
 Duncan Electric Manufacturing Company, La
 Fayette, Ind., a corporation of Illinois

Application December 2, 1944, Serial No. 566,295

2 Claims. (Cl. 171—34)

1

In my Patent No. 2,110,418, I disclosed the use of high coercive magnetic metal, such as Alnico, in the damping magnets of watt-hour meters. One of the important advantages of this metal for this use is in its resistance to weakening by stray magnetic fields such as those encountered due to unusual surges of current caused by lightning or short circuit.

In this matter of withstanding stray fields, the invention represented by that application comprised a tremendous forward step. As compared to the prior conventional damping units, the Alnico damping unit seemed substantially immune to weakening even by lightning surges. As a result of that advance, the standards of the meter industry have been raised to such an extent that there is now some demand for still further stray field resistance. According to the present invention, the immunity of the damping unit is still further increased. For the purpose of illustration, it might be said that the present invention represents almost as much of an advance as did the last in the sense of the percentage of the remaining distance towards perfection which the invention bridges.

Even aside from the desire to obtain greater immunity, there has been a desire to provide other simple ways of using Alnico and like metals and preferably ways that are even simpler at least from the standpoint of permitting the use of simpler shapes of Alnico. Alnico is difficult to machine. The U-shaped magnet of my prior patent constituted one way of using a minimum of machining. According to the present invention, this same minimum of machining of the Alnico is attained with a simpler shape. One of the difficulties in obtaining simplicity without machining has been the difficulty of securing the Alnico in place. According to the present invention, this difficulty is solved by the simple expedient of pressing a simple block of Alnico of rounded cross-section, such as a cylinder, into a tight-fitting sleeve of non-magnetic metal which is provided with securing lugs through which screws may be passed. This non-magnetic sleeve is preferably copper so as to form a shield against the stray alternating fields such as those produced by lightning surges.

Probably the most efficient way to use the flux available from a single cylinder is to divide the flux into two paths so that after passing up through the disk, the two paths will separate and pass downwardly through the disk on opposite sides of the upward flux. This is accomplished by the very simple expedient of securing the en-sleeved Alnico to a U-shaped magnetic yoke which

2

forms the two returned paths, a simple armature being, of course, positioned on the opposite side of the disk. This combination of the magnetic yoke and armature again serves to shield the magnet from surge effects in spite of the fact that it forms the magnetic gaps through which the disk rotates. Thus without any parts that are not otherwise useful, triple protection against stray surge effects is provided producing an extremely high degree of immunity. The three effects are the inherent resistance to weakening of the Alnico or other high coercive metal, the eddy current type of shielding provided by the securing sleeve and the by-passing or shunting type of protection provided by the yoke and armature in spite of the magnetic gaps therein.

Additional objects and advantages will become apparent as the disclosure proceeds and the description is read in conjunction with the accompanying drawings, in which

Fig. 1 is a diagrammatic face view of the meter mechanism chosen for illustration of the invention;

Fig. 2 is a fragmentary view of the structure of Fig. 1 with certain parts removed to expose the damping unit;

Fig. 3 is a fragmentary, vertical, sectional view taken approximately on the line 3—3 of Fig. 1;

Fig. 4 and Fig. 5 are, respectively, plan and front elevational views of the magnet unit of a preferred modification of the invention.

Although the law requires a full and exact description of at least one form of the invention, such as that which follows, it is, of course, the purpose of a patent to cover each new inventive concept therein no matter how it may later be disguised by variations in form or additions of further improvements; and the appended claims are intended to accomplish this purpose by particularly pointing out the parts, improvements, or combinations in which the inventive concepts are found.

The illustrated forms of the invention are shown in conjunction with a watt-hour meter which includes a conventional driving element 11, a conventional frame 12, a conventional disk 13 rotatably carried by the frame, and the damping unit 14 which is the subject of the present invention. In both of the illustrated forms of the invention, the damping unit 14 includes a damping frame 16 which may be secured to the frame 12 or an adapter 17 in any suitable manner. The frame 16 straddles the disk so as to support the magnet unit on one side of the disk 55 and the armature 18 on the other side of the disk.

The magnet unit includes an Alnico magnet 21 of simple cylindrical shape and a yoke 22 of a soft magnetic metal such as mild steel. By soft magnetic metal is meant one which is relatively free of magnetic retentivity and which is easily magnetized.

The magnet 21 may be in its natural cast state except for having its ends ground flat and parallel. It is secured to the yoke 22 by a sleeve of non-magnetic metal which is in a stretched condition around the cylinder 21 and is secured to the yoke 22 by suitable screws 24. The stretched condition of the sleeve 23 is obtained by making it initially of a slightly smaller internal diameter than the external diameter of the magnet 21 and pressing the sleeve over the magnet, or the magnet into the sleeve with a suitable power press. The screws 24 may be threaded into holes in the sleeve 23.

Alternatively, the sleeve 23 may be provided with lugs or ears 26 bent therefrom or secured thereto and through which screws 27 may pass to screw into the yoke 22 as seen in Figs. 4 and 5.

The yoke 22 may be secured to the frame 16 in any suitable manner as by screws 28.

The armature 18 may be formed in one piece or, for the sake of providing adjustability, it may be formed in three pieces, the central portion being an adjustable plug moved forwardly and rearwardly by adjustment screw 29. A suitable construction is illustrated in my prior Patent No. 2,252,483. In this instance, however, the plug should be considerably wider than that there illustrated because of the different nature of the magnet. Alternatively, the adjustment could be obtained by moving the whole armature, the lower magnet unit including the magnet and yoke, or the entire damping unit.

Any suitable form of temperature compensation may be provided. For example, one or more strips 31 of suitable metal having a negative temperature coefficient of permeability may extend from one end to the other of the magnet 21. These may be secured by being held against the magnet by the sleeves 23 and if desired, this sleeve may be initially grooved to receive them, although the groove should not be quite as thick as the strip 31. By making the sleeve 23 of slightly larger internal diameter than it would be without the strip 31, the grooving may be dispensed with.

To obtain a high degree of magnetic efficiency, it is desirable that the magnet 21 be in direct contact with the yoke 22. This may be ensured by having the magnet 21 project at least one or two thousandths of an inch below the sleeve 23.

In addition to the advantages of simplicity and triple protection against weakening by stray fields described above, the form of magnet here contemplated will, by some modification, lend itself to an additional advantage. It has long been recognized to be desirable to be able to remove the disk from the meter without disturbing the damping unit. The present style of damping unit with the single magnet and two return paths on opposite sides thereof lends itself to accomplishing this result. This is because the zone immediately across the center of the magnet, crossing in a front to rear direction is relatively unimportant. The flux from the magnet 21 tends to concentrate near the sides of the magnet toward the poles 32 of the yoke 22. The central portion of the armature 18 can be removed with little effect. By omitting the central portion of the armature and producing a complete gap at

this point free of other obstructions, a channel is formed for the passage of the shaft 33 of the disk through the damping unit. Of course in this event, the frame 16 should not straddle the disk but instead the armature 18 should be carried directly by the main frame 12. This will leave an unobstructed passage for the disk to be drawn out between the armature and the magnet unit. In this event, the lower bearing of the disk, or the portion thereafter carried by the disk, preferably will not extend more than slightly below the lower face of the disk. If necessary, however, the magnet 22 and sleeve 23 could be notched to permit passage of this bearing.

Of course some features of the invention can be used without others when for any reason it is not desired to take full advantage of the benefits which can be obtained by the preferred form of the invention. For example, one leg of the yoke could be omitted, thus providing an essentially C-shaped structure. Also the shielding advantage could be obtained without using the sleeve for securing the magnet and some of the shielding advantages could be obtained even if the non-magnetic shield were omitted. On the other hand, the use of the sleeve which is in stretched condition on the magnet for securing the magnet is itself very useful even if none of the other features shown are provided. In fact, this could be a very useful way of securing a magnet even in very different apparatus. Other shapes of magnet could be used, and some other simple shapes, especially blocks of rounded cross-section, such as circular, oval or rectangular with rounded corners, are nearly as advantageous as cylinders. A slight taper toward the exposed pole might be beneficial.

I claim:

1. A damping unit for watt-hour meters including a magnet of highly retentive magnetic metal in the form of a simple straight block having oppositely facing pole faces, a shielding and flux-carrying structure comprising a plurality of pieces of substantially non-retentive magnetic metal, jointly forming with the magnet a magnetic circuit with two aligned disk-receiving gaps therein magnetically in series with each other and the magnet, said pieces with said gaps jointly forming within said circuit a low-reluctance magnetic path extending from one pole-face laterally away from the magnet, lengthwise of the magnet, laterally toward the magnet and to the other pole-face, one of said pieces in said circuit being in contact with one of said pole faces; and a preformed body of highly electro-conductive metal surrounding said magnet substantially from one pole face to the other and additionally serving to hold said magnet in position.

2. A damping unit for watt-hour meters including a magnet of highly retentive magnetic metal in the form of a simple straight block having oppositely facing pole faces, a shielding and flux-carrying structure comprising a plurality of pieces of substantially non-retentive magnetic metal jointly forming with the magnet a pair of magnetic circuits with the magnet as a common element and with at least three aligned disk-receiving gaps therein, of which gaps two are in each circuit magnetically in series with each other and the magnet, and said pieces with said disk-receiving gaps jointly forming within each of said circuits a low reluctance magnetic path extending from one pole face laterally away from the magnet, lengthwise of the magnet, laterally toward the magnet and to the other pole face;

one of said pieces being in contact with one of said pole faces and extending therefrom in one direction to a gap in one circuit, and in the other direction to a gap in the other circuit; and a pre-formed body of highly electro-conductive metal surrounding said magnet substantially from one pole face to the other and additionally serving to hold said magnet in position.
